UNITED STATES PATENT OFFICE.

JOSEPH CAVE, OF PHILADELPHIA, PENNSYLVANIA, ASSIGNOR TO THE SMITH, KLINE & FRENCH COMPANY, OF PENNSYLVANIA.

DESIGN FOR A BOTTLE-STOPPER.

SPECIFICATION forming part of Design No. 22,582, dated July 4, 1893.

Application filed March 18, 1893. Serial No. 466,718. Term of patent 14 years.

To all whom it may concern:

Be it known that I, JOSEPH CAVE, a subject of the Queen of Great Britain and Ireland, residing in the city of Philadelphia and State of Pennsylvania, have invented a certain new and original Design for Bottle-Stoppers, of which the following is a specification.

In the accompanying drawings Figure 1 represents a view of the bottle stopper embodying my design as seen from above, and Fig. 2 is a side view of the same.

The design is especially applicable to glass bottle stoppers, and consists of the figure of an eagle or similar bird, with a duplicated

front, and having its wings partially open, 15 standing upright on top of the cylindrical portion of the stopper. Both sides of the bird are alike, so that the obverse and reverse of the figure are the same.

Having thus described my invention, I claim—

The design for a bottle stopper, substantially as herein shown and described.

JOS. CAVE.
